4 Claims. (Cl. 214—6)

This invention relates to pallet loading mechanism and is concerned more particularly with a novel pallet loader for automatically depositing tiers or layers of non-rigid packages, such as bags, upon a pallet with the packages in a tier in close contact and the tops of the packages lying approximately in a plane.

Automatic loaders for depositing tiers of packages, such as cartons, upon pallets are now commercially available and, in one such machine, the cartons delivered to the loader are placed upon a stripper disposed above a support, on which an empty pallet has been placed. The cartons are placed upon the stripper in the general arrangement which they are to have in a tier on the pallet and, when the stripper has received the cartons required for a tier, the stripper is moved in a horizontal plane beneath an abutment at one side of the support. As the stripper is so moved, the cartons are held back by the abutment and the group of cartons is also compressed from the sides, so that the cartons are forced into close contact. Continued movement of the stripper, while the cartons are held by the abutment, causes the stripper to move from beneath the cartons and they drop upon the pallet. The support for the pallet is then lowered a step, the stripper is moved back over the support, and the operations are repeated, until the pallet is fully loaded.

In the use of the automatic loader described for loading pallets with large non-rigid packages, such as paper bags holding 100 lbs. of loose sugar, difficulties have been encountered in transferring the bags from the stripper to the pallet and, at the same time, maintaining the bags in contact and with their top surfaces approximately in a plane. The reason is that, as the stripper is moved from beneath a group of bags and the bag or bags near the trailing edge of the stripper start to drop off, these bags have a tendency to slide laterally relative to the support with the result that they may come to rest partly off the support out of contact with adjacent bags and with their upper surfaces at an angle to the horizontal. Such bags are unstable and, if other bags are deposited upon them, an unstable load is produced, which may lose bags or may cause the pallet to be turned over while it is being stored.

The present invention is, accordingly, directed to the provision of automatic loader for depositing nonrigid packages, such as bags, upon pallets to form tiers, which are properly centered upon the pallets and in which the bags lie in close contact and with their upper surfaces substantially in a plane. In the new loader, the bags are placed in the desired tier arrangement upon a main stripper and are moved into close contact just before the main stripper starts to move beneath an abutment. As the movement of the main stripper continues, so that it passes from beneath the tier of bags held back by the abutment, the edges of the bags remote from the abutment and dropping off the trailing end of the stripper are supported by an auxiliary stripper, which has been moved into place above the support. The auxiliary stripper prevents sidewise movement of the bags first released from the main stripper and it remains in position, until the main stripper is about to move wholly

2

from beneath the tier. At that point, the auxiliary stripper moves away from the main stripper and the tier drops upon the pallet on the support. A tier so deposited is properly oriented and the bags in the tier are in close contact and have upper surfaces lying substantially in a plane. The tier is stable and it provides a suitable support for overlying tiers and insures a stable load.

For a better understanding of the invention, reference may be made to the accompanying drawings, in which

FIG. 1 is a plan view of apparatus embodying the invention for loading bags upon pallets;

FIG. 2 is a partial plan view of the apparatus on FIG. 1 on an enlarged scale and with parts broken away.

FIGS. 3 and 4 are sectional views on the lines 3—3 and 4—4, respectively, of FIG. 2;

FIGS. 5A, 5B, and 5C are diagrammatic vertical sectional views showing the apparatus at different stages in its operation;

FIG. 6 is a diagrammatic plan view showing two different arrangements of four bags forming a single tier; and

FIG. 7 is a plan view of two different arrangements of three bags forming a single tier.

The pallet loading apparatus shown in the drawings comprises a conveyor 10, to which the bags are delivered by any suitable means, such as a gravity conveyor 11. The conveyor 10 is formed of a row of parallel rollers 12 mounted in side frame members 13 and having shafts carrying gears 12a driven by a motor 14 through a chain 15. A plurality of stop plates 16, 17, and 18 are mounted between respective pairs of the rollers 12 and may be automatically raised to form stops in different positions for bags being advanced by the rollers.

At one side of the conveyor 10 is a housing 19 containing a ram 20 mounted for movement across the conveyor parallel to the roller axes. The ram is provided with a rack 21, by which it may be advanced over the conveyor and returned into the housing by a pinion 22 meshing with the rack and driven by a motor 23.

A main stripper 24 is mounted at the side of the conveyor 10 opposite the housing 19. The main stripper is formed of a row of parallel rollers 25 with their axes at right angles to the axes of the rollers 12 and side frame members 26, 27, in which the rollers are mounted. The stripper is mounted for movement in its plane toward and away from the conveyor 10 on a pair of rails, of which only the rail 28 (FIG. 3) is shown. The frame member 26 carries a rack 29 on its under surface and the stripper is moved by a pinion 30 meshing with the rack and driven by a motor 31.

As the bags are advanced by the conveyor 10, the first bag B1 of the group to form a tier intercepts the beams issuing from sources 32, 33 and normally falling on photocells 34, 35, respectively. These photocells are in circuit with a control mechanism, which determines the arrangement of the bags in a tier and controls the action of a pusher 36 and an interceptor arm 37. The pusher comprises a hydraulic cylinder 38, the piston rod 39 of which carries an enlarged head 40 and, when the pusher is actuated, the head 40 strikes a bag on the conveyor 10 near the rear end of the bag and swings it to the position of the bag B4 (FIG. 2). At the same time, the arm 37 is moved in over the conveyor to engage the adjacent corner at the leading edge of the bag and hold back this corner, so that the rollers will turn the bag to a position in which its long axis lies parallel to the rollers.

When the first bag B1 of the group to form a tier has been turned by the pusher 36 and the arm 37, as described, the bag is advanced broadside on until it comes to rest against the stop plate 18 which has been raised

for the purpose. When the next bag B2 is advanced, the control mechanism does not actuate the pusher 36 and the arm 37 so that the bag moves end on until it comes to rest against the stop plate 17, which has been raised. As soon as the bag B2 has engaged the stop plate, the ram 20 is moved forward by its motor 23 and pushes the bags upon the stripper, where they travel on the rollers to come to rest against a stop plate 41 carried by a housing 42 and serving as an abutment. The next bag B3 is advanced without being turned and comes to rest against the stop plate 18, while the final bag B4 is turned and moved broadside on to come to rest against the stop plate 16, which has been raised. As soon as the bags B3 and B4 are in place, the ram moves the bags off the conveyor and upon the stripper to complete the tier, as shown in FIG. 5A.

A support 43 for a pallet P is disposed beneath the main stripper in its initial position adjacent the conveyor 10 and the support can be raised and lowered by suitable means conventionally illustrated as a screw 44. The lowering of the support 43 is controlled by a switch S1 which is operated by a flap 45 mounted on a shaft 46 above the main stripper and normally extending down from the shaft. As the bags are pushed on the main stripper by the ram, the flap is swung to operate the switch and the support is moved down one step to receive a tier of bags.

A closer plate 47 is mounted on the piston rods of a pair of hydraulic cylinders 48, 49 to overlie the main stripper along one side and a fixed stop plate 50 is mounted on arms 51, 52 to overlie the main stripper along its opposite side. As soon as the bags to form a tier have been loaded on the main stripper, the cylinders 48, 49 are actuated to move the closer plate inwardly and push the bags into close contact and against the stop plate 50. The motor 31 is then started to move the main stripper away from the conveyor 10. During such movement of the main stripper, the closer plate remains in place to hold the bags of the tier in contact.

As the main stripper passes beneath the abutment 41, the bags on the stripper are held back and the bags at the trailing end of the stripper, namely, bags B3 and B4, are first released to drop upon the pallet P or a tier of bags previously loaded upon the pallet. As the main stripper moves from beneath these bags, their edges adjacent the conveyor 10 first drop down, so that the bags are momentarily in an inclined position and have a tendency to slide laterally relative to the pallet. Such movement of the bags would separate them from the bags B1 and B2 and the top of the tier would be uneven and the pallet load would be unstable. In order to prevent the lateral movement of the bags, the loader is equipped with an auxiliary stripper.

The auxiliary stripper comprises a carriage 53 formed of an angle bar 54 and side plates 55 having rollers running on a track beneath the track for the main stripper and formed of rails, of which only the rail 56 is shown. Racks 57 are attached to the bar 54 near each end and a pinion 58 on a shaft 59 meshes with each rack. The shaft 59 carries a second pinion 60 in mesh with the rack 61 movable endwise through a guide 62 loosely mounted on the shaft 59. At one end, the rack 61 is pivotally connected to an arm 63 mounted to swing on a fixed pivot 64 and the rack and the arm form a toggle which can be straightened and collapsed by a hydraulic cylinder 65 mounted for swinging movement on a pivot 66 and having its piston rod connected to the arm 63 by a slot and pin connection. When the piston of the cylinder is moved in one direction, the rack 61 is moved to rotate the shaft 59 to move the auxiliary stripper carriage away from the conveyor 10 and return movement of the piston causes the rack to return the auxiliary stripper carriage to its initial position shown in FIG. 3.

The operation of the main and auxiliary strippers is illustrated in FIGS. 5B and 5C. When the main stripper starts to move away from the conveyor 10, the auxiliary

stripper moves with it to the position shown in FIG. 5B, in which the plate 54 overlies the edge of the pallet P adjacent to the conveyor 10. When the auxiliary stripper is in this position and the movement of the main stripper permits the edges of the bags B3 and B4 to drop down as previously explained, these edges of the bags land upon the top of the plate 54 with the result that the bags assume a slightly inclined position with their outer edges higher than their inner edges. The inclination of the bags is such that there is substantially no tendency for them to slide laterally.

The movement of the auxiliary stripper is initiated by the closing of a switch S2 by the main stripper in its outward movement and, when the main stripper approaches the end of its outward travel, it operates a switch S3, which causes the cylinder 65 to straighten the toggle and cause the auxiliary stripper to move out from under the bags resting upon it. The bags then drop into their desired positions and a tier is formed, in which the bags are in close contact and their upper surfaces are approximately in a plane and in position to receive the next tier. When the main stripper has completed its outward movement, the motor 31 is reversed and the main stripper returns to its initial position to receive the bags of the following tier.

When a pallet has been fully loaded and the support is in the lowermost position, the pallet is removed from the support by conventional conveyor means, an empty pallet is placed upon the support, and the support is raised to receive the first tier of another load.

The arrangement of the bags on the pallet may be as shown in FIGS. 6 and 7. FIG. 6 illustrates two different tiers, each containing four bags B1-B4, which are arranged to form a hollow square. In each arrangement, two of the bags have been placed upon the stripper without first having been turned through 90° while the remaining two have been so turned. In FIG. 7, there are shown two different tiers of three bags each and, in one tier, two bags have been turned and one left unturned, while, in the other, the reverse arrangement is used. Regardless of the form of tier employed, the auxiliary stripper functions to prevent lateral displacement of the bags first freed from the main stripper and insures that the pallet loads will be stable.

We claim:

1. A pallet loading mechanism which comprises a support for a pallet, an abutment at one side of the support, a main stripper for receiving a tier of non-rigid packages, means for moving the main stripper beneath the abutment in a horizontal plane from and to a position above the support, the abutment removing the tier of packages from the stripper as the stripper moves beneath the abutment from above the support, an auxiliary stripper disposed at the side of the support remote from the abutment and movable in the direction of movement of the main stripper to and from a position beneath the edge of a tier of packages being removed from the main stripper by the abutment, means for moving the auxiliary stripper, means actuated by the main stripper as it moves away from its position above the support to cause a limited movement of the auxiliary stripper in the same direction as the main stripper and means actuated by the main stripper as it approaches the end of its movement away from its position above the support to cause the auxiliary stripper to move in a direction opposite to the direction of movement of the main stripper.

2. The pallet loading mechanism of claim 1, in which the auxiliary stripper is provided with a rack mounted to extend parallel to the direction of movement of the auxiliary stripper and the means for moving the auxiliary stripper include a pinion engaging the rack, a shaft carrying the pinion, and means including a hydraulic cylinder for rotating the shaft in opposite directions.

3. The pallet loading mechanism of claim 1, in which the auxiliary stripper includes a carriage of about the

width of the main carriage and having rollers at its sides, and a track supports the rollers for movement of the carriage.

4. The pallet loading mechanism of claim 1, in which the auxiliary stripper includes a plate adapted to arrest the downward movement of the edges of the packages first freed from the main stripper by its movement beneath the abutment from above the support.
